UNITED STATES PATENT OFFICE.

WILLIS J. BELLows, OF WALLA WALLA, WASHINGTON.

HOSE-COUPING.

1,104,955.

Specification of Letters Patent. Patented July 28, 1914.

Application filed July 29, 1912. Serial No. 712,192.

To all whom it may concern:

Be it known that I, WILLIS J. BELLows, a citizen of the United States, residing at Walla Walla, in the county of Walla Walla 5 and State of Washington, have invented certain new and useful Improvements in Hose-Couplers, of which the following is a specification.

The device forming the subject-matter of 10 this application, is a detachable coupling, adapted to be employed for connecting removably, the ends of a pair of hose sections.

The invention aims to provide novel 15 means for connecting the inner member of the coupling with the outer member thereof, the construction being such that the members may be separated only when first forcibly thrust together, the members being then drawn in opposite directions.

20 A further object of the invention is to provide a novel form of jaw, adapted to interlock with the inner member, and to provide a novel form of spring means for actuating the jaw.

25 With the foregoing and other objects in view, which will appear as the description proceeds, the invention resides in the combination and arrangement of parts and in the details of construction hereinafter described and claimed, it being understood 30 that changes in the precise embodiment of invention herein disclosed can be made within the scope of what is claimed without departing from the spirit of the invention.

35 In the drawings,—Figure 1 shows the invention in longitudinal section; Fig. 2 is a side elevation; Fig. 3 is a top plan; and Fig. 4 is a detail enlarged from Fig. 1.

In carrying out the invention, there is 40 provided an outer member 1 provided with a flaring mouth 2, the mouth 2 being provided in its interior with one or more packing rings 3. The inner member is denoted by the numeral 4 and includes a conical head 45 5, adapted to fit within the flaring mouth 2 of the outer member 1, the head 5 being surrounded by one or more packing rings 6. The head 5 at its outer end is equipped with a flange 7, defining a recess 8.

50 The outer member 1 is circumscribed by a reinforcing band 9 having spaced pairs of ears 10. Connecting the ears 10 of each pair is a pivot pin 11.

Jaws 12 are shown, the jaws terminating 55 in transverse, curved heads 14, adapted to extend part way around the inner member

4, and to bear thereagainst. The inner faces of the heads 14 of the jaws 12 are flared as indicated at 15, so as to receive, initially, the cone-shaped head 5 of the inner member 4. The inner edges of the heads 14 are equipped with flanges 16, defining recesses 17. The flanges 16 of the heads 14 overlap the flange 7 of the head 5, the flanges 16 registering in the recesses 8, and the flange 7 60 registering in the recesses 17. The jaws 12 are curved to form bearings 18 which surround the pins 11, between the ears 10.

Actuating springs for the jaws 12 are provided, the springs comprising diverging 70 arms 19 united by curved connecting portions 20 which bear against the heads 15 of the jaws 12. As indicated at 21, the arms 19 are curved around the pivot pins 11 upon the outside of the ears 10, the pivot pins 11 75 being equipped terminally with heads 22 which engage the curved convolutions of the arms 19 and hold the same upon the pivot pins. Beyond the pivot pins 11 the arms 19 of the springs are prolonged to form extensions 23 having terminal, angularly disposed fingers 24 which bear against opposed portions of the outer member 1.

Presupposing that the parts 1 and 4 are separated, the operation of the device is as 85 follows. The cone-shaped head 5 of the inner member 4 is inserted into the flaring portions 15 of the jaws 14, effecting a separation of the jaws. Ultimately, the head 5 of the inner member 4 will enter the flaring mouth 2 of the outer member 1, the packing rings 3 and 6 effecting a watertight closure. If the parts 1 and 4 be drawn in opposite directions, it is obvious that the flanges 7 and 16 will interlock, preventing a 90 longitudinal separation of the members 1 and 4, the jaws 12—14 being held engaged with the member 4, by the action of the springs 20—19—23. When it is desired to separate the members 1 and 4, the members 100 will telescope beyond the position shown in Fig. 1, the yieldable packings 3 and 6 permitting such telescoping. When the parts are telescoped, the flanges 7 and 16 of the inner member 4 and of the jaw heads 14, 105 respectively, will move longitudinally out of engagement, whereupon the jaws 12—14 may be swung laterally upon their pivotal mountings 11, so that the flanges 16 of the jaws lie beyond the flanges 7 of the inner member 4. Thereupon, as will be obvious, the inner member 4 may be withdrawn, the

110

coupling being, in this manner, separated readily.

It is to be observed that no matter how strong a pull may be exerted in opposite directions upon the members 1 and 4, these members cannot become accidentally separated, owing to the interlocking relation between the flanges 7 and 16. Further, should the members 1 and 4 be thrust toward each other, the coupling cannot fall apart accidentally, owing to the fact that the jaws 12-14 are thrust against the member 4 by the action of the springs.

Having thus described the invention, what is claimed is:—

A pipe coupling comprising a member with a flared conical mouth, a second member provided with an enlarged conical head, the obliquity of the conical surfaces of the first and second mentioned coupling members being the same, a rearwardly extending flange carried by the second mentioned coupling member at the rear portion of the head thereof, the first mentioned coupling member provided with upstanding spaced ears,

locking arms pivotally disposed between the said ears, said locking arms provided with an offset flange engaging and interlocking with the flange of the second mentioned coupling member, the said locking arms provided with substantially semi-cylindrical ends with conical inner surfaces, the obliquity of these surfaces being similar to the obliquity of the aforementioned surfaces, pliable gaskets carried by the first and second coupling members allowing for limited axial movement after a sealed joint has been effected therebetween, resilient springs carried by the said upstanding ears of the first mentioned coupling member engaging the first mentioned coupling member and the said semi-cylindrical ends of the locking arms, holding the same against radial movement.

In testimony whereof I affix my signature in presence of two witnesses.

WILLIS J. BELLows.
